(57) **CLAIM**

The ornamental design for a cable stayed bridge double arch front facing, as shown and described.

DESCRIPTION

FIG. 1 is a top perspective view of the cable stayed bridge double arch front facing showing my new design;

FIG. 2 is a bottom perspective view thereof;

FIG. 3 is a front elevational view thereof, with the rear elevational view being a mirror image thereof;

FIG. 4 is a top plan view thereof;

FIG. 5 is a bottom plan view thereof;

FIG. 6 is a right side elevational view thereof, with the left side elevation being a mirror image thereof; and,

FIG. 7 is a second perspective view thereof showing a second broken line bridge as environment, and illustrating that the cable stayed bridge double arch front facing of the claimed design may be uniformly repeated as subunits in a larger bridge comprised of any number of subunits placed in a series.

The claim is directed to the cable stayed bridge double arch front facing as depicted in FIGS. 1 through 6. The FIG. 7 view and description depict and describe possible environments that form no part of the claimed design. The broken lines depict environmental structure that forms no part of the claimed design, excepting the broken line ends of the spans, which form the boundaries of the claimed design, and also form no part of the design.
